UNITED STATES PATENT OFFICE.

RALPH E. JONES, OF CAMP MEADE, MARYLAND.

NECKTIE HOLDER.

Application filed May 31, 1928. Serial No. 281,843.

This invention relates to devices for holding neckties in place and acting to prevent the necktie from slipping around to one side into an unsymmetrical position in reference 5 to the collar, and the device further acting to prevent the necktie from sagging and thus exposing to view the collar button or otherwise causing it to present an untidy appearance.

- 10 A further object of the invention is to provide a device of this character which comprises in effect a pin preferably detachably engaged with a central aperture in the collar button and adapted to be inserted into
- 15 the socket or aperture in the collar button after the tie has been tied, the pin under these circumstances projecting outward so that the tie may be then forced downward onto the pin and engaged therewith.
- 20 A still further object is to provide a device of this character having a disk disposed upon the pin so that the pin may be readily removed or detached from the collar button when the tie is about to be untied.
- 25 Another object is to provide a shield for the pointed end of the pin whereby the pin may be readily handled and inserted into the collar button.

My invention is illustrated in the accompanying drawing, wherein:

Figure 1 is an end view of a collar button constructed to support a cravat holder in accordance with my invention;

Figure 2 is a longitudinal sectional view 35 of the collar button with the cravat holder in place;

Figure 3 is a sectional view of the shield which may be used over the pin;

Figure 4 is an elevation of a pin or prong 40 having two disks thereon;

Figure 5 is a view showing the holder in use;

Figure 6 is a fragmentary view of a collar 45 and tie, the tie being raised or lifted to show the manner in which the holder is withdrawn from the collar button when the holder is to be removed.

Referring to the drawings, 10 designates 50 a collar button of any usual or ordinary character but which is provided in its head 11 with a concave socket 12 and a longitudinally extending aperture 13 or bore. The pin 14 is blunt at one end 15, this end being adapted to be inserted in the aperture of 55 the collar button, and the other end of the pin is sharp.

Disposed intermediate the ends of the pin are one or more disks 16. In Figure 2, one disk is illustrated, this disk being beveled at 17. In Figure 3, a pin 14 is illustrated having two disks 16 thereon, these disks being slightly spaced from each other. Where two disks are used, it is not necessary to bevel the margin of the disk. If desired, a tubular shield of celluloid, metal or any 60 other suitable material, designated 18, may be disposed over the sharp end of the pin for the purpose of inserting it within the collar button.

In the use of this device, the collar is but- 70 toned upon the stud or button 10 in the usual manner and then the tie is tied. After being tied, the tie is lifted up so as to expose the collar button and the blunt end of the pin is inserted in the bore 13, the disk bearing 75 against the end of the collar button.

The tie is then forced downward so that the pointed end of the pin will project into the tie and will lock the tie, therefore, against any lateral movement or any tendency to sag, 80 as before stated. When the pin is to be removed, the finger nail is inserted beneath the disk and the pin and tie lifted up together until the pin has become detached from the stud or button, and then the pin may be pulled 85 out of the tie. In order to permit the insertion of the pin without danger of pricking the fingers, the cap or shield 18 may be used in inserting the pin in the collar button.

The pin with the double disk 16 thereon is 90 for use with rather high collars where the pressure exerted by the tie might not be sufficient to hold the pin in place and the tie would work upward or outward and withdraw the pin from the socket. By having the 95 double disk thereon, however, the tie will exert a pushing force upon the pin, holding it firmly in place in the socket.

Obviously the device which I have illustrated is susceptible of modification in many 100 ways without departing from the spirit of the invention as defined in the appended claims. The device is very simple and has been found thoroughly effective for the purpose intended.

105 I claim:

1. The combination with a collar button having a bore longitudinally therethrough, of a detachable necktie engaging prong comprising a straight pin adapted to be axially supported within said bore and projecting therefrom and into a tie, the pin having thereon a 110

disk adapted to bear against the end of the collar button.

2. The combination with a collar button having a bore longitudinally therethrough, of a detachable necktie engaging prong comprising a straight pin adapted to be axially supported within said bore and projecting therefrom and into a tie, the pin having thereon a disk adapted to bear against the end of the collar button, said disk being beveled on one side and around its periphery.
3. A necktie holder comprising a collar button formed with a longitudinally extending, axial bore, and a detachable prong comprising a pin pointed at one end and adapted to be inserted within the bore of the button, the
- 10
- 15

other end being sharp, the middle of the pin carrying a disk adapted to bear against the head of the collar button.

4. A necktie holder comprising a collar button formed with a longitudinally extending, axial bore, a detachable prong comprising a pin pointed at one end and adapted to be inserted within the bore of the button, the other end being sharp, the middle of the pin carrying a disk adapted to bear against the head of the collar button, and a tubular cap detachably engaging over the sharp end of the pin.

In testimony whereof I hereunto affix my signature.

RALPH E. JONES.
